UNITED STATES PATENT OFFICE

2,442,060

PRODUCTION OF AROMATIC HYDRO-CARBONS OF HIGH PURITY

Robert M. Shepardson, Madison, N. J., assignor
to Standard Oil Development Company, a corporation of Delaware

Application May 6, 1943, Serial No. 485,797

4 Claims. (Cl. 260—673.5)

1

This invention relates to high temperature cracking of hydrocarbons under relatively low pressure to produce aromatic constituents.

Steam cracking of hydrocarbon oils or liquid fractions is known for the production of olefins, diolefins, and aromatic compounds. The desired aromatic compounds comprise benzene and toluene but in the ordinary steam cracking operations they are contaminated by undesired paraffins and olefins having substantially the same boiling point and it is impossible, for example, to separate nitration grade toluene from such mixtures by distillation.

Other processes are known in which mixtures of aromatics and paraffins are obtained and the desired aromatics are separated by solvent extraction from the paraffin compounds.

According to my invention, normally liquid hydrocarbons are severely cracked at relatively high temperatures for a relatively short period of time in the presence or absence of a diluent gas to substantially completely destroy all paraffins and olefins in the boiling range of benzene and higher boiling aromatics. With my invention it is possible to crack hydrocarbons, fractionally distill the cracked mixture to separate a toluene fraction and a benzene fraction, acid treat the fractions separately and again distill each fraction to obtain nitration grade of toluene and substantially pure benzene without the necessity of solvent extracting.

In the drawings, Figs. 1 and 1A represent one form of apparatus adapted to carry out my invention, Fig. 1A being a continuation of Fig. 1.

Referring now to the drawings, the reference character 10 designates a line through which the charge stock or feed stock is pumped by pump 12. The charge stocks which may be used in my invention may be any petroleum fraction although heavy naphthas with a boiling point of about 200° F. to 300° F. to about 200° F. to 400° F. are preferred. Virgin fractions from paraffinic or naphthenic type crudes or cracked fractions of more olefinic structure may be used. Diluent gas such as steam, light normally gaseous hydrocarbons, flue gas or other inert gas is introduced into line 10 through line 14. While I prefer to use a diluent, my process may be carried out without using any diluent gas. Instead of using an inert diluent gas, I may use air or other oxygen-containing gas which will aid in raising the temperature of the mixture by burning some of the hydrocarbons and will also lead to the production of flue gas by the resulting combustion.

The charge stock with or without an added

15 diluent gas is passed through a heating coil 16 in reaction zone 18 where the temperature is rapidly raised to about 1200° F. to about 1600° F. The time of reaction is maintained from about a few seconds to a fraction of a second depending on the temperatures used. The temperature during reaction is sufficiently high to destroy substantially all of the paraffin compounds boiling in the desired aromatic range and at the same time olefins, diolefins and desired aromatic compounds are produced.

16 The cracked mixture leaving the reaction zone 18 is immediately quenched to a temperature of about 600° F. to 1000° F. by the introduction of water through line 22. The quenched mixture passes through line 24 into the lower portion of a cooling tower 26 where additional water quench is introduced at the top of the cooling tower through line 28.

17 In the cooling tower 26 the reaction products are cooled to below the boiling point of water so that water and some of the normally liquid hydrocarbons are condensed and are collected in the bottom of the cooling tower. The water forms the lower layer 32 and this water is withdrawn from the bottom of the tower 26 and passed through line 34 and cooler 36. At least a portion of the cooled water is passed through line 38 by pump 42 and returned to the quench lines 22 and 28. If steam is used as a diluent, at least a portion of the water is withdrawn from line 34 through line 44 and removed from the system.

18 In the cooling tower 26 the condensed oil or normally liquid hydrocarbons form the upper layer 46 in the bottom portion of the cooling tower 26 and the liquid hydrocarbons are withdrawn from the tower and passed through line 48 by pump 52. The liquid oil contains olefins, diolefins and the desired aromatic fraction as well as heavier aromatic constituents. The oil is then passed through line 54 and heating coil 56 in a heater 58 and then passed into fractionating tower 62 for separating the oil into the desired fractions as will be presently described.

19 In the cooling tower 26 normally gaseous constituents and some higher boiling constituents are not condensed and pass overhead through line 64 to a compressor 66 where they are compressed to a pressure of about 100 to 600 lbs./sq. in. and the compressed gases are introduced into an absorber 68. Cool absorber oil is introduced into the top of the absorber or absorption tower through line 72 for countercurrent scrubbing of the gases introduced through line 64. During this

scrubbing, desired constituents are recovered from the gas and the gases which are not absorbed pass overhead through line 74 and are vented from the system. Desirable constituents are absorbed in the absorber oil. If it is desired to recover the ethylene, high pressure absorption would be employed, whereas low pressure absorption is satisfactory if only the C₄ and higher boiling fractions are wanted.

The fat absorption oil is withdrawn from the bottom of the absorber 68 through line 76 and is passed through a heating coil 78 in a heater 82 to remove the absorbed constituents from the absorber oil and the heated mixture is then passed to a stripping zone or stripper tower 84 wherein the vaporized constituents are separated from lean absorption oil which is withdrawn from the bottom of the stripper tower 84 through line 86 and pumped through this line by a pump 88. The lean absorber oil is then passed through a cooler 92 and the cooled absorption oil is then returned to the top of the absorption tower through line 72. The separated desired vapors and gases are taken overhead from the stripper tower 84 through line 94 and combined with the oil separated in the cooling tower 26 and the mixture passed through the heating coil 56 above described and into the fractionating tower 62 above described.

In the fractionating tower 62 the mixture is fractionated to separate the cracked products into desired fractions. The fraction going overhead through line 96 may comprise a C₂ through C₅ fraction containing ethylene, propylene, isobutylene, n-butylene, butadiene, pentylene, and the various C₅ diolefins. This gaseous fraction can be further treated in any of the various well known methods to separate any of the desired olefins or diolefins from the remaining constituents. From the upper portion of the fractionating tower 62 another fraction is removed through line 98 and this fraction comprises C₆ paraffins and olefins.

Further down in the tower another fraction is taken off through line 102 and this fraction is a benzene cut containing a large percentage of benzene and a small quantity of olefins and diolefins. Further down in the tower another aromatic fraction is taken off through line 104 and this fraction contains a large proportion of toluene and a small quantity of olefins and diolefins.

Further down in the fractionating tower a heavy naphtha fraction is removed through line 106 and this heavy fraction is removed from the system. The heavy naphtha fraction may be recycled to the heating coil 16 or it may be removed from the system and further treated to produce motor fuel, aviation blending stock, etc. The heavy naphtha fraction is highly aromatic and forms a good motor fuel. By clay treating this heavy naphtha an aromatic motor fuel is obtained. Bottoms comprising tar or fuel oil are withdrawn from the bottom of the fractionating tower through line 108.

The further treatment of the toluene fraction will now be described. This toluene fraction comprises about 97% toluene and some olefins and diolefins and practically no paraffin compounds. The toluene fraction is passed through line 104 by pump 112 and is mixed with an acid such as concentrated sulfuric acid introduced through line 114 to remove olefins and diolefins from the toluene fraction. Preferably a countercurrent system is used with cooling between the stages to reduce sulfonation of the aromatic constituents.

The concentration of the acid is preferably from 90% to 98% and the quantity of acid used or needed will vary depending on the quantity of olefins and diolefins present, about 25 lbs. of sulfuric acid per barrel of toluene fraction generally being sufficient.

The mixture of acid and toluene fraction is introduced into a mixing zone 116 for intimate mixture of the acid and toluene fraction and the mixture is then passed through line 118 to a separator 119. The acid used for mixing with the toluene fraction is acid recovered from a latter separating stage as will be presently described. In the separator 119 acid sludge containing olefins and diolefins settles in the bottom of the settling chamber 119 and is removed from the system through line 122.

The partially treated toluene fraction is then passed overhead through line 124 and through a cooler 126 after which it is mixed with an additional quantity of acid introduced through line 127. This acid is taken from the third separating stage as will be presently described. The mixture of acid and toluene fraction is introduced into a second mixer 128 where further intimate contact between the acid and toluene fraction is brought about. The mixture is then passed through line 134 to a second separating or settling chamber 136 in which the acid separates as a lower layer and is withdrawn from the bottom of the settling chamber through line 114 and pumped through this layer by pump 138. Line 114 introduces the partly used acid into line 104 for admixture with the untreated toluene fraction from the fractionating tower 62 before being passed to the first mixer 116.

The further treated toluene fraction leaves the settling chamber 136 through line 144 and is passed through a cooler 146. Fresh sulfuric acid is introduced into line 144 by line 148 and this mixture is introduced into a third mixing zone 152 where the purified toluene fraction is contacted with fresh acid to further remove undesirable constituents. The mixture is then passed through line 154 to a third settling chamber 156 in which the acid settles as a lower layer and is withdrawn from the bottom of the settling chamber through line 127. The acid is passed through line 127 by pump 162 and is introduced into line 124 as above described for admixture with the partly purified toluene fraction passing to the second mixer 128.

The purified toluene fraction leaves the settling chamber 156 through line 164 and is passed through heating coil 166 in heating zone 168 and then through line 172 into a second fractionating tower 174. In the fractionating tower 174 the toluene fraction is further fractionated and nitration grade toluene meeting the U. S. Army specification is withdrawn through line 176. Bottoms from the fractionating tower 174 are withdrawn through line 178 and overhead gases or vapors from the fractionating tower 174 are passed through line 182. The bottoms and the overhead gases or vapors are combined and passed through line 184 by pump 186 and admixed with the oil or cracked products leaving the cooling tower 26 and this mixture is introduced into the first fractionating tower 62 for the recovery of benzene and toluene which does not quite meet desired purity.

The further treatment of the benzene fraction withdrawn through line 102 will now be described. This benzene fraction is treated in a similar manner to the treatment for the toluene

fraction. The benzene fraction is pumped through line 102 by pump 202 and is mixed with partly used acid from a second settling chamber, the acid being passed through line 204 and introduced into the benzene fraction in line 102. The mixture is passed through a first mixer 206 and the mixture is then passed through line 208 to a first settling chamber 212 in which the acid settles as a sludge containing olefins and diolefins and is withdrawn through the bottom of the settling chamber through line 214 and removed from the process.

The separated benzene fraction in partly purified form is removed from the first settling chamber 212 through line 216 and passed through a cooler 218 after which it is mixed with partly spent acid from the last settling chamber, the partly spent acid being passed through line 220. This mixture is passed to a second mixing zone 222 and the mixture is passed through line 226 to a second settling chamber 228 in which the acid settles as a bottom layer. This acid is the partly spent acid which is returned through line 204 by pump 234 for admixture with the impure benzene fraction being introduced into the purifying system.

The separated partly purified benzene fraction leaves the settling chamber 228 through line 236 and is passed through cooler 238 after which it is mixed with fresh sulfuric acid introduced through line 242. This mixture is passed to a third mixing zone 244 and then through line 246 to a third settling chamber 248 in which the partly spent acid separates as a bottom layer. This bottom layer is passed through line 220 by pump 254 and is the acid which is mixed with the partly purified benzene fraction passing through line 216 after the first purifying step.

The purified benzene fraction is withdrawn from the settling chamber 248 through line 256 and is passed through a heating coil 258 in a heating zone 262 to heat the fraction to distillation temperature. The heated fraction is then passed through line 264 and is introduced into the lower portion of a third fractionating tower 268 for separating benzene of about 99+ % purity. The purified benzene is withdrawn through line 272. The bottoms are withdrawn through line 274 from the fractionating tower 268. Overhead vapors and gases are withdrawn through line 276. The bottoms and overhead vapors and gases are mixed and passed through line 278 for admixture with the overhead vapors and bottoms from the second fractionating tower 174 for return to the first fractionating tower 62. The bottoms and overhead vapors or gases from the third fractionating tower 268 contain impure benzene which is returned to the first fractionating tower 62 for further treatment.

The time of mixing of acid and the benzene or toluene in each mixing zone is about 3 minutes. A settling time in each separating chamber following mixing is about 5 minutes. I am not to be limited exactly to these times as they may be varied within limits without departing from my invention. The acid treatment is carried out at temperatures so that the benzene and toluene are in liquid phase.

My invention is especially adapted for cracking heavy naphthas to produce exceedingly pure benzene and toluene. In the following example East Texas heavy virgin naphtha having a boiling range of about 250° F. to 400° F. was cracked in the presence of steam at about 15 lbs. gauge pressure. The amount of steam used was about 80

mol percent. In the following data the two columns compare the results obtained by practicing my invention to produce pure toluene and benzene with an operation for producing maximum butadiene.

Steam cracking East Texas heavy virgin naphtha (250-400° F.) at 15# pressure in the presence of 80 mol per cent steam.

		Operation Giving Nitration Grade Toluene After Acid Treating	Operation Giving Maximum Butadiene
15	Temperature °F.	1,400	1,375
20	Feed Rate, v.v./hr. to Highest Temperature Coil	2.9	8.9
	Times of Contact seconds	0.83	0.27
25	Yields:		
	C ₄ Free Gas wt. per cent	51.5	39.8
	Ethylene do	15.3	14.1
	Total C ₁ do	5.65	10.07
	Butadiene do	2.99	3.83
	Isobutylene do	1.67	2.47
	N-butylene do	0.74	3.64
	Total C ₂ do	2.00	6.03
	Isoprene do	0.37	1.65
	Piperylene do	0.47	1.42
30	Debutanized Gasoline Vol. per cent	26.0	45.2
35	Toluene do	5.4	3.1
40	Benzene do	7.6	2.3

In the first and more severe operation described above, the fraction boiling from 170° F. to 240° F. contained only 3% to 6% of olefins and diolefins and the paraffin concentration was less than 1%. This paraffin concentration is sufficiently low to preclude the necessity for solvent extraction and as described below, the olefins and diolefins were readily removed by acid treatment. In the second or less severe operation giving maximum butadiene, however, the benzene and toluene fractions contained 40% to 60% of olefins and diolefins which past experience has shown cannot be satisfactorily removed by acid treatment without tremendous losses of the desired aromatics.

The cracked products passing to the fractionating tower 62 from the first or more severe operation above were fractionated in a one hundred plate distillation tower to separate a toluene fraction and a benzene fraction. The separate fractions were then treated with about 25 lbs. of 98% sulfuric acid per barrel of oil passing to the fractionating tower 62.

After the acid treatment, the benzene and toluene fractions were each passed to a separate fractionating tower comprising a 40 plate column in which these purified fractions were separately fractionated. The toluene produced satisfactorily met U. S. Army specification for nitration grade toluene and the benzene was about 99.5% purity.

As above pointed out, the operating temperature range is about 1200° F. to 1600° F. but for the treatment of heavy naphthas a temperature of about 1400° F. is preferred.

Data have been obtained indicating the time of contact required at various temperature levels to effect cracking of the hydrocarbons of sufficient severity to destroy the paraffins thus permitting the production of pure benzene and toluene without solvent extraction. The empirical formula for this correlation in the temperature range of about 1200° F. to 1600° F. is as follows. The temperature (T) in degrees Fahrenheit must be equal to or greater than $1332 - 107.6 \log S + 10S^{-1.45}$ where S is the actual time of contact in seconds at the temperature T.

Since in most cases the cracking will not be carried out at a constant temperature level, it will

be necessary to correct the times of contact at the various temperature levels to a time of contact at a common temperature level. This can be accomplished with the aid of the empirical formula in which all points obtained are of equal cracking severity. The following equation can be used to calculate equivalent contact time at any temperature level.

Equiv. time at y temp. =

$$\text{Time req'd. at } y \text{ temp.} \quad \text{Time at } x \text{ temp.}$$

¹ Time required to destroy paraffins in boiling range of aromatics according to my invention.

For example, if there is an operation in which the time of contact is 0.2 second at 1300° F., 0.2 second at 1350° F. and 0.2 second at 1400° F. and 0.1 second at 1450° F., the equivalent time of contact at 1450° F. in each zone is as follows:

$$\text{At } 1300^\circ \text{ F.} \quad \frac{0.2}{2.2} \times 0.3 = 0.027 \text{ second at } 1450^\circ \text{ F.}$$

$$\text{At } 1350^\circ \text{ F.} \quad \frac{0.2}{0.95} \times 0.3 = 0.064 \text{ second at } 1450^\circ \text{ F.}$$

$$\text{At } 1400^\circ \text{ F.} \quad \frac{0.2}{0.49} \times 0.3 = 0.120 \text{ second at } 1450^\circ \text{ F.}$$

$$\text{At } 1450^\circ \text{ F.} \quad \frac{0.1}{0.1} = 0.100 \text{ second at } 1450^\circ \text{ F.}$$

$$\text{Total} \quad 0.311 \text{ second at } 1450^\circ \text{ F.}$$

In the above data the 2.2 factor is obtained by using the empirical formula to obtain the time required at 1300° F. to obtain the degree of cracking required by my invention. The denominators in the 1350° F. and 1400° F. are similarly obtained for these temperatures. The 0.3 factor is obtained from the formula by solving for the time required at 1450° F.

The total above shown is greater than 0.3 and as this is the equivalent time for cracking at 1450° F., these conditions are sufficiently severe to destroy paraffins and come under the operating conditions set forth in my invention.

When employing cracking conditions on normal petroleum hydrocarbons fulfilling the requirements of the above empirical formula, it has been found that the concentration of paraffins in the fraction boiling from 170° F. to 240° F. from the product is not over 1 volume per cent, with olefin and diolefin concentration varying from 2 to 9 volumes per cent and aromatic concentration exceeding 90 volume per cent. Because of the almost complete absence of paraffins and the low concentration of olefins or diolefins, acid treatment followed by distillation to remove polymers is sufficient to produce aromatics of greater than 99% purity. With milder cracking conditions, however, solvent extraction in addition to acid treatment is necessary to obtain aromatics of this purity.

After acid-treating the benzene and toluene cuts, they may be given usual water washing treatment followed by usual alkaline washes to remove acidic constituents.

While I have shown one form of apparatus and have included a specific example, it is to be understood that these are by way of illustration only and my invention is not to be limited thereto.

I claim:

1. A method of producing an aromatic fraction

in the gasoline boiling range from relatively heavy naphthas which comprises heating heavy naphtha containing paraffin constituents to a temperature of about 1400° F. for a period of time in the range of about 0.5 of a second to about 1.0 second to substantially completely destroy the paraffinic constituents in the naphtha in the boiling range of the desired aromatic fraction and form aromatic compounds and olefins and diolefins, fractionating in a rectifying column the cracked products to separate therefrom an aromatic fraction in the desired boiling range substantially free of paraffinic compounds and of normally gaseous olefins, further treating the aromatic fraction thus separated with concentrated sulfuric acid to remove olefins and diolefins therefrom and distilling the treated aromatic fraction to recover a substantially pure aromatic fraction in the desired boiling range.

2. A method according to claim 1 wherein the aromatic fraction freed from olefins and diolefins is subjected to distillation thereby yielding nitration grade toluene.

3. A method according to claim 1 wherein the aromatic fraction freed from olefins and diolefins is subjected to distillation thereby yielding benzene of over 99% purity.

4. A method according to claim 1 wherein diluent gas is mixed with the naphtha before heating to 1400° F.

ROBERT M. SHEPARDSON.
